GEORGE J. MILLER, OF BALTIMORE, MARYLAND, ASSIGNOR TO WISE BROTHERS, OF BALTIMORE, MARYLAND, A FIRM COMPOSED OF EDWARD H. WISE, LEO H. WISE, AND HENRY E. WISE.

COMBINED WAIST-LINE SUPPORTING AND ADJUSTING MEANS FOR GARMENTS.

1,154,584.

Specification of Letters Patent. Patented Sept. 21, 1915.

Application filed January 28, 1915. Serial No. 4,814.

To all whom it may concern:

Be it known that I, GEORGE J. MILLER, a citizen of the United States, residing at Baltimore, in the State of Maryland, have invented certain new and useful Improvements in Combined Waist-Line Supporting and Adjusting Means for Garments, of which the following is a specification.

This invention relates to improvements in waist line adjusting and supporting means for garments and has particular reference to a combined supporting strap to be engaged by the suspender tab which will also form part of an adjusting means about the waist line of the garment.

It has heretofore been common to provide around the waist line of garments, straps which form loops, through which latter the suspender ends may be passed so as to support the garment. In addition to the supporting strap-loops, garments have also been provided with adjusting tabs or lacings, either at the sides or in the rear of the garment to effect an adjustment of the garment about the waist of the wearer. As heretofore practised, however, these adjusting and supporting devices have been separate and independent of each other and therefore a matter of expense both in material and labor in the manufacture of the garment. By means of the present invention the supporting and adjusting devices are combined, and are positioned on the garment where they are accessible for ready adjustment.

The invention is illustrated in the accompanying drawing, in which,—

Figure 1 shows a fragment of the upper portion of a garment to which the improvement is attached, which latter is shown in side view. Fig. 2, illustrates the same, the adjusting tape however being untied and hanging loosely. Fig. 3, shows a top plan or edge view of the garment with the adjusting tape drawn and tied as when adjusted, and also shows the loops formed in the strap for receiving the suspender ends or tabs. Fig. 4, shows the garment in top plan to illustrate the positions of the improved devices thereon, and Fig. 5, illustrates the garment in front view.

In the present instance the improvement is shown as applied to a pair of drawers but the same may be applied to other garments.

Referring to the drawing, the numeral 6, designates a drawer garment which in the present instance has a facing 7, around the upper edge, and is provided with a fly-opening 8, of usual construction at the front. By means of my invention, it is unnecessary to provide any vertical slits extending from the upper edge downwardly except the fly or placket opening. At each side of the fly or placket opening, and at a point where the front suspender-ends are ordinarily located, I provide the garment with a strap 9, which preferably extends substantially parallel with the upper edge 10, of the garment. This strap has its two ends securely fastened to the garment by means of stitches 11, and between its two secured ends said strap has two spaced apart perforations 12, and 13, respectively. In the present instance these perforations have the form of circular holes or eyelets whose edges are button-hole stitched. A tape 14, extends along the inner side of the strap 9, and one end 15, of said tape passes through the perforation 12, while the other end 16, of the tape extends through the perforation 13, in the strap. It will thus be understood that in the present instance a portion of the tape extends along the inner side of the strap from one perforation to the other and that the two ends 15 and 16, project through the perforations respectively from the inner to the outer side of the strap. While this particular arrangement of tape is not essential to the invention, it presents a neat appearance and its attachment is facilitated, as will now be explained. Substantially midway between the two perforations 12 and 13, I pass a series or row of stitches 17, through the strap 9, and also through the tape 14, and into the material of the garment, so that said stitches will permanently secure said strap, tape and garment material together in a vertical line that crosses both the strap and tape. This row of stitches 17, also forms two loops 18 and 19, respectively in the strap, so that the perforation 12, will be located in the looped portion 18, of the strap, while the perforation 13, will be located in the loop 19, of said strap. It will thus be seen that the strap 9, is stitched at its opposite ends and also midway between its ends to the garment, as usual in support.

ing straps, and that it also has two tape ends that project from said two loops in such a way that when those ends are drawn toward each other and tied as at 20, the two attached ends of the strap will be drawn toward each other which produces folds or a plait 21, in the strap and takes up the garment around the waist by drawing on the latter through the securing stitches 11.

10 By securing the tape and strap to the garment by the stitches 17, which also form the loops in the strap, the tape cannot be lost because of its permanent attachment.

Having thus described my invention, what

15 I claim is,—

1. The combination with a garment having a waist-band, of a strap having its opposite ends secured to the waist-band, said strap also being secured to the band between 20 its opposite ends to form two loops, and means for drawing the said two loops toward each other to shorten the distance between said opposite ends.

2. A garment having a suspender-engaging strap secured in a looped condition thereto and tape-ends depending from spaced-apart points on the looped strap for shortening the latter and adjusting the garment about the waist.

30 3. A garment having the opposite ends of a suspender-engaging strap secured thereto and formed into a loop, and two tape ends projecting from the strap from opposite sides of a point midway between the two attached ends of the strap said tape-ends when

drawn together and tied serving to adjust the garment about the waist.

4. The combination with a garment, of a strap having its opposite ends secured to the garment near the upper edge of the latter said strap also being secured to the garment between its ends to form two loops and a tape-end projecting from each loop of the strap which ends when drawn together will adjust the garment about the waist.

45 5. The combination with a garment, of a strap having its opposite ends secured to the garment said strap having spaced-apart perforations and a tape having its ends projecting through the two perforations in the strap said ends when drawn together serving to adjust the garment about the waist.

50 6. The combination with a garment, of a strap having its opposite ends secured to the garment said strap having spaced-apart 55 perforations, a tape extending along the side of the strap between said perforations and having its ends projecting through said perforations and means for securing the strap and tape to the garment at a point between said perforations whereby the ends of the tape may be drawn toward each other and tied and thereby adjust the garment about the waist.

60 In testimony whereof I affix my signature 65 in presence of two witnesses.

GEORGE J. MILLER.
